UNITED STATES PATENT OFFICE.

FREDERICK SCHWARTZ, OF BROOKLYN, NEW YORK.

DESIGN FOR A BRIDGE LAMP OR THE LIKE.

Application filed January 9, 1928. Serial No. 24,786. Term of patent 7 years.

To all whom it may concern:

Be it known that I, FREDERICK SCHWARTZ, a citizen of the United States, and a resident of the borough of Brooklyn, city of New York, county of Kings, and State of New York, have invented a new, original, and ornamental Design for a Bridge Lamp or the Like, of which the following is a specification, reference being had to the accompanying drawing forming a part thereof.

The figure of said drawing is a perspective view of a bridge lamp of my new design.

I claim:

The ornamental design for a bridge lamp or the like, as shown.

FREDERICK SCHWARTZ.
